CIGARETTE CASE

Romeo Capocci, Chicago, Ill.

Application September 23, 1950, Serial No. 12,326

Term of patent 7 years

(Cl. D85—2)

To all whom it may concern:

Be it known that I, Romeo Capocci, a citizen of the United States, residing at Chicago, in the county of Cook and State of Illinois, have invented a new, original, and ornamental Design for a Cigarette Case, of which the following is a specification, reference being had to the accompanying drawings, forming a part thereof.

Fig. 1 is a perspective view of a cigarette case showing my new design, the cover being shown in partly open position.

Fig. 2 is a side elevational view of the same.

Fig. 3 is an end elevational view of the same.

Fig. 4 is a top plan view of the same.

I claim:

The ornamental design for a cigarette case, substantially as shown.

ROMEO CAPOCCI.
